US0D1113245S

(12) United States Design Patent (10) Patent No.: US D1,113,245 S
(45) Date of Patent: * Feb. 17, 2026

(54) LIQUID DISPENSER

(71) Applicant: Scent Theory Products LLC, New York, NY (US)

(72) Inventors: Kevin Gindi, Brooklyn, NY (US); Ana Angel Rodriguez, Cincinnati, OH (US); Amy Alperin, New Rochelle, NY (US)

(73) Assignee: Scent Theory Products LLC, NY (US)

() Term: 15 Years

(21) Appl. No.: 30/005,570

(22) Filed: May 27, 2025

Related U.S. Application Data

(63) Continuation of application No. 29/990,521, filed on Feb. 21, 2025, now Pat. No. Des. 1,077,516.

(57) CLAIM

The ornamental design for a liquid dispenser, as shown and described.

DESCRIPTION

FIG. 1 is a perspective view of a liquid dispenser;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines in the drawings show portions of the liquid dispenser and form no part of the claimed design.

1 Claim, 5 Drawing Sheets
